UNITED STATES PATENT OFFICE.

ORA S. BROWN, OF VIRGINIA, MINNESOTA.

CLOTHES-WASHING MACHINE.

Application filed February 27, 1922. Serial No. 539,480.

To all whom it may concern:

Be it known that I, ORA S. BROWN, a citizen of The United States, residing at Virginia, in the county of Saint Louis and State of Minnesota, have invented certain new and useful Improvements in Clothes-Washing Machines; and I do declare the following to be a full, clear, and exact description of the invention, such as will enable others skilled in the art to which it appertains to make and use the same.

This invention relates to an improved washing machine which is especially, but not necessarily, designed for washing clothes.

One object of the invention is to generally improve upon machines of this class by providing one wherein a novel electric heater is arranged in the water space of the tub between the latter and movable clothes cylinder, the heater being advantageous in that it permits free and rapid circulation of water, and being so designed that it tends to direct the water into the cylinder.

More specifically speaking, it is another object of the invention to devise a novel heater for use in connection with machines of this class, the heater comprising a heat absorbing and retaining element which is heated by electricity and is housed within a casing which the water directly contacts.

A further object of the invention is to devise a machine of this class wherein the heater is held immovably and against displacement in the water drum by novel anchoring means.

Other objects and advantages of the invention will be apparent during the course of the following description.

In the accompanying drawings forming a part of this specification and in which like numerals are employed to designate like parts throughout the same:

Figure 1 is a central vertical section, with the clothes container in elevation, of a washing machine constructed in accordance with this invention.

Figure 2 is a section taken on the line 2—2 of Fig. 1.

Figure 3 is a horizontal section taken on the line 3—3 of Fig. 2.

Figure 4 is an enlarged detail section taken on the line 4—4 of Fig. 3.

In the drawings, the numeral 1 designates a suitably designed tub supported on the frame 2, the tub being open at the top and a

removable cover 3 being employed to close this opening when the machine is in operation. Arranged inside of the tub is a removable clothes cylinder 4 having a stub axle 60 5 at its left hand end resting on a bearing 6 secured on the inner wall of the adjacent end of the tub. On the opposite end of the cylinder is another stub axle 7 having connection with a slidably mounted drive shaft 8 driven and controlled by the usual means (not shown). The tubular clothes container or cylinder shown is of the slatted type but of course, may be of any other suitable construction.

The bottom of the tub is spaced a considerable distance from the clothes cylinder and a novel heating device is arranged in this space for heating the surrounding water. While this heater may be constructed otherwise, it preferably comprises a transversely curved elongated metal casing 9 having a removable cover 10 bolted or otherwise removably secured in place to permit insertion and removal of a heating element 80 11 which is arranged inside of the casing. This heating element is preferably in the form of a brick composed of a substance which will absorb and retain heat for a considerable length of time. The brick 11 85 is shaped similar to the casing and has its edges spaced from the inner faces of the latter, the same being provided at its corners with feet 12 which rest on the bottom of the casing and space it therefrom. A 90 plurality of electric wires 13 are arranged about the brick in any suitable manner for the purpose of heating it to a high degree. In order to permit passage of these wires into the casing and to prevent the entrance 95 of water and undue movement of the casing, the latter is provided at one end with an opening from which a tubular and short neck 14 extends, this neck bearing at its free end against a packing member 15 surrounding it and engaging the inner side of the tub (see Fig. 4). This neck 14 is internally screw-threaded and a threaded bushing 16 is fitted therein and extended through an opening in the wall of the tub and beyond 100 said opening to permit a binding nut 17 to be arranged thereon for drawing the free end of the neck into tight engagement with the packing member and tub. A fluid-tight connection of the heater with the tub is 110 thus provided and the heater is prevented from being displaced by the splashing water.

Attention is here directed to the fact that the aforesaid casing 9 is provided at its corners with feet 18 which rest on the bottom of the tub and serve to space the casing a sufficient distance therefrom to permit free circulation of water during the washing operation or when the tub is being drained. I also wish to direct attention to the fact that the opposed longitudinal sides of the casing are inclined as indicated at 19, so that they will serve to direct or guide the water into the clothes cylinder.

The operation and manner of using the improved washing machine is doubtless understood and the manner in which the improved electric heater contributes to insure success of the invention has been made clearly apparent by the foregoing description when taken in connection with the drawings. Therefore, it seems entirely unnecessary to enter a more detailed description.

Since probably the best results may be obtained with the construction and arrangement herein shown and described, this is taken as the preferred embodiment of the invention. However, I wish it to be understood that minor changes coming within the scope of the invention as claimed may be resorted to if desired.

I claim:

1. In a washing machine, a tub designed to contain a cleaning fluid, a clothes cylinder rotatable in the tub and spaced from the bottom thereof, said cylinder being equipped with openings to permit the circulation of water therethrough, and a body lo-

cated in said tube and spaced from both the cylinder and bottom of the tub to permit free circulation of the cleaning fluid, 40 the opposed longitudinal sides of said body converging toward said clothes cylinder to direct the fluid through the openings in said cylinder when the latter is set into rotation.

2. In a washing machine, a tub, a clothes containing cylinder rotatable in said tub and spaced above the bottom thereof to provide a water space, said cylinder being formed with openings to permit circulation 50 of the fluid therethrough, and a casing located in the space between the cylinder and bottom of the tub, said casing having its opposed longitudinal sides converging toward the cylinder and said casing being spaced 55 below said cylinder and equipped with legs resting on the bottom of the tub to space it from said bottom to permit free circulation of the fluid.

3. A device of the class described comprising a body for disposition in a fluid tub under an apertured clothes cylinder therein, said body being adapted to be spaced from both the cylinder and the bottom of the tub to permit free circulation of the cleaning fluid, and the opposed longitudinal sides of said body converging toward said clothes cylinder to direct fluid through openings in said cylinder when the same is set into rotation.

In testimony whereof I have hereunto set my hand.

ORA S. BROWN.
